UNITED STATES PATENT OFFICE

154,762

DESIGN FOR A CRADLE TELEPHONE ACCESSORY

Milan R. Forkapa, East Cleveland, Ohio

Application May 20, 1949, Serial No. 2,790

Term of patent 14 years

(Cl. D26—14)

To all whom it may concern:

Be it known that I, Milan R. Forkapa, a citizen of the United States, residing in East Cleveland, in the county of Cuyahoga and State of Ohio, have invented a new, original, and ornamental Design for a Cradle Telephone Accessory, of which the following is a specification, reference being had to the accompanying drawing, forming part thereof. This application is a continuation-in-part of my pending application, Serial No. D. 141,349, filed September 12, 1947.

In the drawing

Fig. 1 is a side perspective view of a cradle telephone accessory, showing my new design;

Fig. 2 is a top plan view;

Fig. 3 is a front elevational view; and

Fig. 4 is a perspective view showing the back and underside of my design.

I claim:

The ornamental design for a cradle telephone accessory, substantially as shown.

MILAN R. FORKAPA.
